WALTER F. HINKLE, OF CHICAGO, ILLINOIS.

CALIPERS.

1,285,175.

Specification of Letters Patent. Patented Nov. 19, 1918.

Application filed October 22, 1917. Serial No. 197,773.

To all whom it may concern:

Be it known that I, WALTER F. HINKLE, a citizen of the United States, residing at Chicago, in the county of Cook and State of Illinois, have invented a certain new and useful Improvement in Calipers, of which the following is a specification.

My invention relates to calipers, and the object is to provide a construction whereby both "inside" and "outside" measurements may be taken and read directly from appropriate scales. In connection with this principal object it is my purpose to provide jointed arms,—that is, arms made of two sections articulately connected together, which may be bent to different angles, one for taking inside and another for taking outside measurements. In another position the caliper is folded up to reduce the space occupied when not in use. A subsidiary object is to provide a self locking lock for holding the two sections of the arms in their different relative positions—also to make said locks yieldable under pressure exerted in a direction to change the angle of the arm sections. Still another object is to so arrange the scales and their reading lines or indices as to compensate for the changed positions of the outer sections of the arms relatively to the main or inner sections when altered for inside and outside measurements. Contributory objects will become evident as the description proceeds.

I accomplish my objects by the construction shown in the accompanying drawings, in which:

Figure 1 is a face view of the caliper adjusted to take "outside" measurements. In this figure the zero position is shown in full lines.

Fig. 2 is a face view of the caliper adjusted to take "inside" measurements. In this figure, the zero position is shown in full lines.

Fig. 3 is a sectional view on the line 3—3, Fig. 1.

Fig. 4 is a sectional view on the line 4—4, Fig. 2.

Fig. 5 is a sectional view on the line 5—5, Fig. 1.

Fig. 6 is an edge view of the parts as shown in Fig. 2.

Fig. 7 is an edge view showing the caliper folded.

Similar numerals refer to similar parts throughout the several views.

In carrying out my invention I provide two arms pivoted together, each arm consisting of a main or inner section and an outer section pivoted thereto. In the drawings, the main sections 1 and 2 are connected by a pivot 3. The outer sections 4 and 5 are connected at the outer ends of the sections 1 and 2, respectively, by means of pivots 6. The outer sections have fingers 8 for contacting the object to be measured. Outer sections 4 and 5 contact the inner or proximate faces of the main sections 1 and 2, and said main sections are properly spaced apart to accommodate them. In the particular design shown, the section 2 has a hub 10 which acts as a spacer.

The inner faces of the outer sections 4 and 5 are smooth so that they may pass each other. In order to increase the range of usefulness of the device, I have provided means for holding the outer sections at different angles with respect to the inner sections. For example, when outside measurements are to be taken, the outer sections are bent toward each other, as shown in Fig. 1. When inside measurements are to be taken, the outer sections are straightened so as to lie proximately in line with the inner sections, as shown in Fig. 2. I have provided self locking means for holding the outer sections in their different positions. The means provided consist in the present case of flat springs 12 fastened to the outside of the main sections 1 and 2 and carrying knobs 13 which fit into holes 14 formed adjacent to the pivot 6 and concentric therewith. The knobs are preferably rounded and the construction and coaction is such that when the outer sections are brought to the relative positions shown in Fig. 1, the knobs will snap into one of the holes 14 and will hold the outer sections against any ordinary force. But by exerting extra force, the operator may straighten out the outer sections, as shown in Fig. 2, or may fold them longitudinally inward, as shown in Fig. 7. When thus exerting force, the operator will cause the knobs to recede from the holes they were

in at first and automatically enter one or the other of the succeeding holes, depending upon the position to which the operator brings the outer sections. In other words, 5 I have provided a self locking lock for holding the outer sections in the various positions desired, said lock yielding if sufficient pressure is exerted by the operator. Depressions 16 are formed in the outer surfaces of 10 the main sections 1 and 2 to afford room for the operator to grip the sides of the springs 12 and deliberately lift the knobs 13 out of the holes 14 if he prefers this to the automatic operation.

15 My caliper is self indicating and, in the present illustrated form, shows the readings both in inches and centimeters and fractions thereof. According to the design shown, the main section 1 has four sight apertures, 20 20, 21, 22 and 23. Each of these has a pointer for coöperating with the proximate scale, which passes adjacent to it when the main sections are rotating, as they are in the taking of measurements. The pointer 25 24 coöperates with the scale 25 to read the outside measurement in inches. The pointer 26 coöperates with the scale 27 to read the outside measurement in centimeters. These scales are shown in Fig. 1. The pointer 28 30 coöperates with the scale 29 to read the inside measurement in inches, and the pointer 30 coöperates with the scale 31 to read the inside measurements in centimeters. These scales are shown in Fig. 2. All four of these 35 scales are concentric with the main pivot 3, but the "outside" scales and the "inside" scales are angularly offset to allow for the different positions of the arm sections when adjusted for inside or outside measurements. 40 This not only gives the instrument a greater field of usefulness, but causes the scale which is not being read to be covered up by the overlying disk of the superposed main section. In other words, the user cannot make 45 any mistake by reading the wrong scale because it will be hidden from view.

In operation, if the user wishes to take outside measurements, he adjusts the outer sections 4 and 5 to an oblique angle with the 50 inner or main sections, as shown in Fig. 1. This increases the scope of the instrument for with this adjustment, for example, it would be possible to measure the thickness of the web of a channel iron or I-beam, the 55 arms being bowed to clear the flange. When the fingers 8 are brought into contact with the object to be measured, the scales 25 and 27 may be read opposite the respective indices 24 and 26, thus showing inches and 60 centimeters, respectively, and fractions thereof. At this time the scales 29 and 31, shown in Fig. 2, will be hidden by the disk portion of the apertured main section 1. If 65 the user wishes to take inside measurements, he re-adjusts the outer sections 4 and 5, and

brings them approximately to straight line position, as shown in Fig. 2. He then brings the fingers 8 into contact with the object to be measured, whereupon he may take a direct reading from the scales 29 and 31 70 which show inches and centimeters, respectively, and fractions thereof. In reading the last mentioned scales, he uses the index 28 or 30, depending upon whether he wishes to read the measurement in inches or centimeters. At this time the scales 25 and 27 will be hidden. It will thus be seen that the device is a direct reading instrument, both when used as an inside caliper and as an outside caliper and is adjustable so that its 80 range of utility may exceed the range of the ordinary caliper. There is no danger of the operator's reading the wrong scale for only the proper scale will be revealed. When the operator is through using the instrument, he folds the outer sections 4 and 5 inward, as shown in Fig. 7, thus bringing the instrument to very small compass. The outer sections will be automatically locked in all of their contemplated positions and, 90 as the result of this automatic locking, the operator may be sure that when the sections are locked they are accurately positioned.

Having thus described my invention, what I claim as new and desire to secure by 95 Letters Patent, is:

1. A caliper having jointed arms provided with self-locking means for locking the joints of the arms automatically in either of two definite positions, one for inside and the other for outside measurements, and two scales, one in position to correctly indicate the measurement when the outer sections are adjusted to take outside measurements and the other in position to correctly indicate the measurement when the outer sections are adjusted to take inside measurements.

2. A caliper having two arms pivoted together, and each consisting of two sections 110 pivoted together, each arm being provided with self-locking means for automatically locking the outer sections in either of two definite positions relatively to the respective main or inner sections for taking inside and 115 outside measurements, the locking positions being symmetrical in each instance, and two scales, one in position to correctly indicate the measurement when the outer sections are adjusted to take outside measurements and the other in position to correctly indicate the measurement when the outer sections are adjusted to take inside measurements.

3. A caliper adapted for both inside and 125 outside measurements, said caliper having two arms pivoted together, each arm comprising two sections pivoted together, and locks for holding the outer sections of each arm in predetermined relation with the 130

inner section thereof, one for taking inside measurements and the other for taking outside measurements, the locking positions being such that the two arms as a whole will 5 be symmetrical when adjusted for taking inside measurements and symmetrical when adjusted for taking outside measurements, said locks being yieldable whereby they will release when pressure is applied, and two 10 scales, one in position to correctly indicate the measurement when the outer sections are adjusted to take outside measurements and the other in position to correctly indicate the measurement when the outer sections are 15 adjusted to take inside measurements, the arms being capable of passing each other, whereby zero measurements can be taken in outside measurements and almost as low as zero measurements may be taken on inside 20 measurements.

4. An indicating caliper having two arms pivoted together, each arm consisting of two sections pivoted together and adapted to maintain different definite positions relatively to each other for taking inside and outside measurements, and two scales, one for indicating inside and the other for indicating outside measurements.

5. A caliper having two arms pivoted together, each arm consisting of two sections pivoted together for taking internal and external measurements, locking means on each arm for holding the outer sections in either one of two definite acting positions, the two 35 outer sections maintaining the same angular relation to the inner sections when adjusted for outside measurements, and maintaining the same angular relation to the inner sections when adjusted for inside measurements, and two scales, one in position to correctly indicate the measurement when the outer sections are adjusted to take outside measurements and the other in position to correctly indicate the measurement when the 45 outer sections are adjusted to take inside measurements.

6. A caliper having two arms pivoted together, each arm consisting of two sections pivoted together and capable of maintaining different positions relatively to each other for taking inside and outside measurements, the inner section of one of the arms having two scales concentric with the main pivot of the arms, said scales being angularly offset 55 to compensate for the changed positions of the outer sections of the arms.

7. A caliper having two arms, each arm consisting of a main and an outer section pivoted together, the main sections of the 60 arms being pivoted together, the main and outer sections of each arm being capable of maintaining different positions relatively to each other for taking inside and outside measurements, the main section of one of the 65 arms having two scales both graduated

in inches and concentric with the main pivot but at different distances from said pivot, and the other main section having two pointers or indices, one passing adjacent to one of said scales and the other to the other. 70

8. A caliper having two arms, each arm consisting of a main and an outer section pivoted together, the main sections of the arms being pivoted together, the main and outer sections of each arm being capable of 75 maintaining different positions relatively to each other for taking inside and outside measurements, the main section of one of the arms having two scales graduated in inches and concentric with the main pivot, but at 80 different distances from said pivot, and the other main section having two indices, one passing adjacent to one of said scales and the other to the other, one of said indices pointing radially inward and the other 85 pointing radially outward toward their respective scales.

9. A caliper having two arms, each arm consisting of a main and an outer section pivoted together, the main sections of each 90 arm being pivoted together, the main and outer sections of each arm being capable of maintaining different positions relatively to each other for taking inside and outside measurements, the main section of one of the 95 arms having two scales graduated in inches and concentric with the main pivot but at different distances from said pivot and angularly offset to compensate for the changed positions of the outer sections of the arms, 100 and the other main section having two indices, one passing adjacent to one of said scales and the other to the other.

10. A caliper having two arms, each arm consisting of a main and an outer section 105 pivoted together, the main sections of each arm being pivoted together, the main and outer sections of each arm being capable of maintaining different positions relatively to each other for taking inside and outside 110 measurements, the main section of one of the arms having two scales graduated in inches and concentric with the main pivot but at different distances from said pivot and angularly offset to compensate for the changed 115 positions of the outer sections of the arms, and the other main section having two indices, one passing adjacent to one of said scales and the other to the other, one of said indices pointing radially inward and the 120 other pointing radially outward toward their respective scales.

11. A caliper composed of two arms, each arm having a main section pivoted to the main section of the other arm and having an 125 outer section pivoted at its outer end, said arms being capable of passing each other to enable inside and outside measurements to be taken, means for locking the outer sections at different angles with respect to their 130

respective main sections for taking inside and outside measurements respectively, a scale graduated in inches on the inner surface of one of the main sections for indicating inside readings, the other main section having a sight aperture for revealing said scale, and an index for reading it, another scale graduated in inches on the inner surface of the scaled main section for indicating outside readings, the apertured main sec-

tion having a sight aperture for revealing the last mentioned scale and an index for reading it, the two scales being radially offset, and also angularly offset to compensate for the different adjusted positions of the outer sections and to render one of the scales hidden when the other scale is revealed. 15

In witness whereof, I have hereunto subscribed my name.

WALTER F. HINKLE.
